UNITED STATES PATENT OFFICE.

JOHN T. BELL, DECEASED, LATE OF SAN FRANCISCO, CALIFORNIA, BY JOSEPHINE T. BELL, ADMINISTRATRIX, OF SAN FRANCISCO, CALIFORNIA.

DAVIT TACKLE-BLOCK.

1,273,315.

Specification of Letters Patent. Patented July 23, 1918.

Application filed January 8, 1917. Serial No. 141,152.

To all whom it may concern:

Be it known that JOHN T. BELL, deceased, formerly a citizen of the United States, residing at the city and county of San Francisco and State of California, did invent a new and useful Improvement in Davit Tackle-Blocks, of which the following is a specification.

This invention relates to improvements in davit tackle blocks, and consists in a means for controlling the releasing hook of such blocks, by which the boat or other device is suspended, in such a manner that both ends will be released simultaneously and without danger.

It also comprises details of construction which will be more fully described by reference to the accompanying drawings, in which:

Figure 1 is an edge view, showing the hook engaged in full lines and disengaged in dotted lines.

Fig. 2 is a top plan view.

As here shown, A is a block of the ordinary oval shape, having an open channel through it between the upper and lower ends, within which the pulley 2 is journaled. The suspending ropes from the davit attachment may attach to the block at 3 and thence up over a pulley above, thence down around the pulley 2 and continue in the usual well-known manner for the application of power to raise or lower the boat.

The attachment 3 consists of reinforcing bars extending from top to bottom on each side of the pulley opening, passing below the lower end and uniting to form an eye 4 to receive a bolt 5, from which the hook 6 is suspended, and this hook engages a ring at the end of the boat, and two of these hooks suspend the ends of the boat from the davits.

When a suspended boat is released at the time when it is to be floated upon the water, difficulty is experienced in releasing both ends at the same time, and if that is not done, one end may be held to its suspending support, while the other end, having been dropped will cause the boat to take such a position that its load will be thrown into the sea. In the present invention it is designed to provide for the retention of the boat in its suspended state, until the sea is in such a condition that both ends may be disengaged at once and the boat be dropped substantially level and in safety.

In order to do this, the hook 6 has an extension arm 7, curving from the suspending eye around the lower end of the block up along one side of the block to near the upper end, where it has a hinged and flattened attachment 8, and this may terminate in an eye 9 for the attachment of a releasing cord. In order to insure the two hooks remaining in position and not being disengaged unexpectedly by the heaving of the sea a clamping device 10 is fixed to the side of the block in such a position as to engage and hold the part 8. The clamp 10 is of elastic material, like spring steel, and is bent to form a base, and two outwardly extending parallel members at right angles with the base, between which the part 8 is held with a sufficiently elastic pressure to require a slight force to detach it and allow the hook 6 to be inverted about its supporting bolt 5 and thus enable disengagement of the end of the boat supported thereby.

By hinging the part 8 to the arm 7, close to the elastic clamp 10, it provides a leverage such that a slight pull upon the two eyes 9 will disengage the connection and rise of the boat will allow the hooks to invert simultaneously and insure the falling of the boat on an even keel.

The transverse base of the clamp 10 passes across within the pulley channel where it is secured, the parallel elastic arms passing out through slots in the side of the block and appearing exteriorly thereto. The hooks 6 are held by the leverage of the arms 7 and the elastic clamps 10 and may be held indefinitely until the swell or movement of the waves is such that the boat may be safely launched, when a pull upon the cords connecting with the eyes 9 will release the arms 7 and the rise of the boat from the hooks 6 will allow them to invert and release the boat.

Having thus described my invention, what I claim and desire to secure by Letters Patent is—

1. In a boat detaching apparatus, a tackle block, a boat supporting hook pivotally supported from the lower portion of the block and formed with a rigid arm extending up alongside of the block, a latch pivoted to the upper end of the arm for being disposed in alignment therewith alongside the block and adapted to be swung outwardly therefrom, the upper end of said latch be-

ing bent outwardly in loop form to provide an eye, and means carried by the block for detachably engaging the latch to hold it alongside the block.

5 2. In a boat detaching apparatus, suspending pulley blocks having hooks fulcrumed and turnable below the blocks, arms integral with the hooks extending upward along the side faces of the blocks with 10 latches hinged to the upper ends having eyes for pull attachments, and clamps fixed to the blocks between which the latches are retained.

3. In a boat detaching apparatus of the 15 character described, pulley blocks having invertible hooks fulcrumed at the lower end, and having extension lever arms with hinged latch attachments, and clamps having transverse bars secured to the interior of the 20 block with elastic parallel arms extending through the face of the block to engage and retain the latch attachments.

4. In a boat detaching apparatus, a tackle

block, a boat-supporting hook pivotally supported from the lower portion of the block 25 and formed with a rigid arm extending up alongside of the block, a pivoted latch on the upper end of the arm adapted to be swung outwardly from the block and provided with a transverse enlargement, and a 30 U-shaped spring clasp secured within the block and having its resilient clamping elements extending outwardly through slots in the block to be reinforced thereby, the outer end portions of the resilient clamping elements being curved inwardly to engage the 35 transverse enlargement of the latch.

In testimony whereof I have hereunto set my hand in the presence of the two subscribing witnesses.

JOSEPHINE T. BELL,
Administratrix of the estate of John T.
Bell, deceased.
